COMBINATION SHEET-CONTAINING FRAME AND BENEFICIATING REAGENT RECEP- TACLE

Lloyd D. Benedict, Chicago, Ill., assignor to Marie Isadora Malone, Catherine Marcella Campion, and Grace Beata Cheevers, Chicago, Ill., a partnership

Application March 17, 1947, Serial No. 735,266

8 Claims. (Cl. 312—352)

This invention pertains to a new and improved type of a cabinet. It is particularly directed to those types of cabinets used in homes, offices, factories, stores and in public places that generally serve as a repository for a deodorizing agent or for an odor absorbing agent. Not only can it be used in the many places mentioned hereabove, but it is possible to utilize this improved and new type of a cabinet in any place where it is desirable to disseminate an odor within a desired space or conversely to remove an odor from an enclosed space. Likewise, it can be used to diffuse an odorous substance such as para-dichlorobenzene, naphthalene, into the atmosphere to controveine and counteract any undesirable odors that prevail within the treated space.

In addition to the above function, there is another function performed efficiently by this cabinet. By providing the face of the cabinet with a frame, it is possible to mount therein any desirable object useful for its aesthetic, cultural or utilitarian value. For instance, it has been found quite highly useful to mount within said frame of the cabinet, a mirror, picture or any other display of various kinds.

It may also be desirable, to utilize a portion of the face of the cabinet enclosed by the frame to display thereon some pertinent message advertising the wares of a manufacturer. The balance of the face may have a mirror, picture or anything else desired.

When the improved type of cabinet is used then this matter can be very conveniently and readily changed and removed by an authorized person. Unauthorized or mischievous persons are deterred and even prevented in their attempts to tamper with contents.

Furthermore, the construction of the cabinet is so designed and devised that no one can tamper with the interior of the frame or of the reagent holding receptacle unless a special key is provided to unlock the entire cabinet assembly.

It therefore is one object of this invention to provide a cabinet with a receptacle for a reagent that is capable of beneficiating the atmosphere within the treated space.

Another object of this invention is to provide a means whereby advertising messages and other notices can be displayed conspicuously in an attractive but useful manner.

A still further object of this invention is to provide a means whereby the said display or other exhibit is securely fastened behind a pane of glass neither of which can be tampered with by the public unless they are destroyed.

A still further and additional object of this invention is to provide for the beneficiating reagent, a receptacle that can be readily and conveniently opened, charged and closed effectively against tampering by malicious individuals of the public.

These and other objects, adaptations, variations and modifications of the fundamental concepts underlying the principles of this invention can be readily discerned and devised by one skilled in this art particularly in light of the clear, lucid and definite description given hereinbelow and as further shown and illustrated in the annexed drawings forming a part of this disclosure.

10 These should not be considered under any condition expressed or implied as a limitation of any nature or kind of the principles underlying this invention but should be considered purely as illustrative of one of the many possible applications to which this invention can be readily adapted.

In the drawings, Figure 1 is a vertical view, partly broken away and in section showing one of the many applications.

25 Figure 2 is a section taken along lines 2—2 of Figure 1, and showing in detail the construction of the frame and reagent receptacle.

Figure 3 shows an edge view of the frame and its integral side extension bent inwardly to the face which forms the wall for retaining therebetween the reagent containing receptacle. In addition it shows the lock used to retain the contents of the receptacle and frame intact and free from mischievous hands.

30 35 Like numerals used as reference characters herein designate like parts in the different views of the drawings.

The improved type of a display cabinet consists of a back or base 10 which may be made of any suitable material such as a galvanized or otherwise treated metallic sheet, plastic, etc. Along its outer edge and preferably substantially most of the distance of the two sides and all of the bottom end is an outstanding and inwardly directed flange 12. This flange 12 forms a channel-like rim 14 about most of the outer perimeter of the said backing 10. The upper part and end of the said backing 10 terminates into a straight edge and is free of the said flange 12. Though for illustrative purposes the flange 12 extends along the longitudinal edges and lower end of said backing 10, it may if desired, extend about both ends and provide an open space midway of the face of the backing 10, to provide for attaching to the said backing 10, the receptacle 18. Like-

wise, if it is desired, the receptacle 18 may be attached to the lower end of the backing 10. If used in this manner it may be utilized as a shelf by a slight change in contour.

Near the upper part of the longitudinal edges of said backing 10, are two outstanding substantially semicircular tab-like extensions 16 that are folded at right angles to the base 10. A curved receptacle 18 of such form and shape as to fit between the said tab-like extensions 16 is provided to hold the air beneficiating reagent. A number of perforations or openings 20 are placed therein to provide the reagent access to the air so that it can perform its function of beneficiating the atmosphere. The end walls 22 of the receptacle 18 are in close juxtaposition with the said tab-like extensions 16. A retaining wall 24 extends transversely across the back of the receptacle 18 to form a hollow between itself and the curved front wall portions to retain therein the reagent in position and to prevent it from pouring down along the base face 19 into the cavity provided for display purposes beneath the receptacle 18. The receptacle 18 is held in place and juxtaposition between the said tab-like extensions 16 by rivets 26 or some other means which also acts as a shaft about which the receptacle can swing into an open or closed position as shown in detail in Figure 2. The rotatable hinge 26 is so placed in position on the tab-like extension 16 that entry is permitted to remove or replace the contents of the cavity below the receptacle 18.

For sake of convenience, it is preferred that the receptacle 18 is so pivoted about the axis 26 that its center of gravity automatically forces it into an open position when the restraining bolt and nut lock means 28 is removed. This action facilitates easier removal of the advertising matter and contents from the interior of the display cavity and the receptacle 18.

A long bolt 28 is inserted transversely thru holes 30 bored in the walls of the outer tab-like extensions 16 and the end walls 22 of the receptacle 18. A capped nut 32 of a lock design having therein three holes to receive a similarly shaped pronged key, engages the threads of the bolt 28 and fastened tightly into place by means of such key. It locks the receptacle in place to prevent pilfering and unauthorized tampering of the contents of the receptacle as well as of the contents held in the cavity space beneath the said receptacle. For illustrative purposes, the drawings show a round nut having in its face three holes. Into these fits a pronged key of substantially similar spatial arrangement which grips the nut and then it can be readily fastened tight. It is obvious that other types of closures can be used, but it has been found that this particular type is effective for the general purpose of preventing substantially tampering of the contents by unauthorized persons.

The cavity 14 provided by the inturned flanges 12 contains sufficient space to retain therein placards, pictures, mirrors, glass, etc. that may be desired to be placed on exhibition. A pane of glass 34 is retained between the inturned flanges 12. Any other suitable material such as any of the transparent plastics, like polystyrene, acetates, methacrylates, etc. may also be used in place of glass to provide a non-breakable surface. Between the backing 10, and the glass 34 is inserted a message or placard 36, or a mirror 38, or a picture 40, or anything else of somewhat similar nature that one may wish to display to

the general public or within the home. A spacer (not shown) may be used if the displayed material is very thin. It is obvious that these inserts such as the placard, pictures, advertising, etc. can be readily removed by opening the receptacle 18, and swinging it about the pivoted hinge 26. When the receptacle is replaced in the closed position, the contents of the receptacle and of the cavity below the receptacle are firmly locked against intruders by the tightened lock nut 32.

Though not forming a part of this invention, the reagent that is used in the beneficiation of the atmosphere may consist of the various chlorinated aliphatic and aromatic compounds or other well known materials such as toluene, naphthalenes, activated charcoals, etc. It is preferred to use these in tablet form to permit a larger active surface area.

It is quite obvious that it is possible to vary considerably the details, modifications, extensions and variations of this invention as well as of the specific illustrations given above and embodying this invention, without departing from the spirit and scope of the fundamental concepts underlying the principles of this invention as described herein and defined in the hereunto appended claims.

I claim:

1. A cabinet for displaying information and treating air, comprising a flat backing, one end and substantial portions of the longitudinal edges thereof having an inturned flange, an opening in said flange at its uppermost portion whereby sheet-like material may be inserted into and retained therebetween, tab-like projections extending outwardly from said backing near uppermost portions of said longitudinal edges and in juxtaposition to said openings, a receptacle for air beneficiating reagents suspended across the top of said openings between said tab-like extensions, a means for pivotally mounting said receptacle between said tabs and a means to lock the said receptacle against the flat backing, whereby the said sheet-like material is held within the flange and simultaneously the receptacle is closed.

2. In the combination of claim 1, wherein the said flanges along the perimeter of said sheet terminates substantially about the bottom of the ends of said mounted receptacle, the said receptacle pivotally mounted between said outwardly extending projections, the said receptacle when open permits the sheets to slide past it into the recesses formed by said inturned flange and when closed its lowermost edge rests on top of the opening of said flange and said sheets inserted therebetween.

3. In the combination of claim 1, wherein the face of said receptacle is a container having apertures therein and is mounted in close parallel juxtaposition with said backing.

4. A combination deodorizer and advertising message display cabinet suitable for use in public areas and being substantially tamperproof comprising a flat backing sheet, tab-like projections extending outwardly at right angles to said backing sheet about the uppermost portions of the longitudinal edges of said backing sheet, an outwardly projecting but inwardly facing flange forming a perimeter about the balance of said edges of said flat backing sheet, a transparent sheet and advertising message engaged by said flange-like perimeter, a receptacle mounted between said tabs directly over the opening of said flange and across the face of said backing sheet, a means to

open said receptacle and a means to lock said receptacle.

5. In the combination of claim 4, wherein the said tab-like extensions and perimeter are an integral unit with said backing sheet.

6. In the combination of claim 4 wherein the bottom of the said receptacle has an upwardly extending transverse rear wall.

7. In the combination of claim 4, wherein the said receptacle is axially mounted within the said tab-like extensions the said axial mounting being offset to center of said receptacle whereby it can open automatically to receive a charge of air treating reagent when the lock is removed.

8. A combined display and deodorizing cabinet comprising a backing sheet having inwardly disposed flange-like members about substantial portions of the edges of said sheet, one or more transparent sheets engaged by said flange-like members, a display mounted between said transparent sheet and said backing sheet, inte-

gral tab-like projections extending forwardly from said backing on the edges near the open end, a receptacle for air beneficiation reagents mounted directly across the opening of said space enclosed between the outstanding flange-like members, a means to mount said receptacle and a means to lock the said receptacle whereby the contents of said receptacle and said sheets held between said outstanding flanges are rendered substantially tamperproof.

LLOYD D. BENEDICT.
